(57) **CLAIM**

The ornamental design for a power supply with buckle, as shown and described.

DESCRIPTION

FIG. 1 is a front view of a power supply with buckle design showing my new design.

FIG. 2 is a rear view of a power supply with buckle.

FIG. 3 is a left side view of a power supply with buckle.

FIG. 4 is a right side view of a power supply with buckle.

FIG. 5 is a top view of a power supply with buckle.

FIG. 6 is a bottom view of a power supply with buckle.

FIG. 7 is a perspective view of a power supply with buckle, shown with contracted buckles; and,

FIG. 8 is another perspective view of a power supply with buckle, shown with open buckles.

The power supply with buckle is shown with symbolic dot-dash pattern break lines. The appearance of any portion of the article between the break lines forms no part of the claimed design.

Evenly-Spaced broken lines in the drawings show portions of the power supply with buckle that form no part of the claimed design.
